PRESS FOR CUTTING SHEET METAL

Charles Joseph Rhodes, Wakefield, England

Application January 17, 1947, Serial No. 722,653
In Great Britain November 6, 1946

5 Claims. (Cl. 164—102)

1

This invention relates to presses for cutting sheet metal and particularly to presses of the "open cap" or "over-hanging" type. In presses of this type, due to the overhang, the C-shaped frame is liable to "spring" or deflect to an appreciable extent under full load or pressure and to compensate for this deflection it is customary to so construct such presses that the surface of the work table and the face of the ram are slightly out of parallel, so that under full load or pressure the two faces lie in parallel planes. This expedient, however, has a deleterious effect on the cutting edges of the dies causing them to wear rapidly.

In order to neutralise the adverse effects of the deflection of the C-shaped frame, in a press of the above type it has previously been proposed to arrange the ram to slide on a pair of vertical rods, supported by the lower part of the press frame at points below the work table and extending above the work table, said rods also carrying brackets with bosses at one end through which said rods pass and bosses at their other end through which slide another pair of vertical rods supported at their ends by the cam in parallel relationship to the first-mentioned pair of vertical rods.

According to this invention the ram is guided for reciprocation by grooves of part-circular cross-section formed therein sliding on part-cylindrical members rigidly secured to a bracket carried on upright pillars, which pillars are supported by the lower part of the press frame at points below the work table and extending above the work table.

The part-cylindrical slides are extremely accurate and require a minimum of setting. Moreover the new arrangement enables a much lighter ram of cheaper construction to be employed.

Preferably the bracket is adjustably mounted on the upright pillars, so that it may be adjusted upwards or downwards to conform with adjustments made in the stroke of the ram. If, for example, the ram were so adjusted to accommodate certain dies that it projected too far below the slides at the bottom of the stroke, a certain loss of rigidity and accuracy would take place, but this loss may be obviated by a corresponding downward adjustment of the bracket.

The ram is operated from a crank pin by means of a coupling.

One embodiment of the invention will now be described and illustrated with reference to the accompanying drawings, in which:

Fig. 1 is a diagrammatic side elevation,

2

Fig. 2 is a detail front elevation, and
Fig. 3 is a cross section on the line 3—3 of
Fig. 2.

Referring to the drawings which only illustrate the parts of a press of the "open gap" or "overhanging" type that are necessary for the understanding of the invention, the reference numeral 1 indicates the gapped and substantially C-shaped frame, the upper part of which overhangs the lower part 2, having depending wings 3 and supporting the work table 4.

Bolts 24 and 25 are provided for securing the frame to a base.

The lower parts of two vertical rods 5 of suitable diameter to ensure rigidity are mounted in and secured by set screws to deep bosses 6 formed on the wings 3. A bracket 7 is supported on the rods 5 by means of split bosses 8, through which the rods pass. The bosses may slide on the rods 20 or may be clamped thereto by tightening clamping screws 9. The bracket is provided with tail pieces 10 terminating in internally screw-threaded bosses 11 in which adjusting screws 12 engage.

In order to adjust the height of the bracket 7, the clamping screws 9 are slackened and the adjusting screws 12 are turned to move the bracket upwards or downwards to the desired position, whereupon the clamping screws are again tightened.

Each front face 13 of the bracket 7 is machined to a flat, and a part-cylindrical steel slide bar 14 having a flat ground along its whole length is secured to each face 13 with the flat on the bar 14 presented to the flat on the face 13. The bars are secured to the bracket by means of a number of bolts 15 spaced along their length. The ram 16 has two lateral projections or gibbs 17 in which corresponding part-cylindrical 40 grooves are machined and two axially spaced detachable part-cylindrical bushes 18, 19, which are a sliding fit over the slide bars 14, are provided in each groove.

As the reciprocal movement of the ram 16 is effected in the usual manner by the crank 20 mounted in the upper part of the frame 1 of the press and operated by means of a coupling 22, and the ram 16 is not mounted in the frame, it will be obvious that any deflection of the frame is not transferred to the ram.

I claim:

1. A press for cutting sheet metal comprising an upright C-shaped frame, a work table supported by the lower part of said frame, a plurality of upright pillars supported by the lower part

of said frame at points below said work table and extending above said work table, a bracket carried on said pillars above said work table, a plurality of upright part-cylindrical members rigidly secured to said bracket, and a ram having a plurality of grooves of part-circular cross-section formed therein, said grooves co-operating with and sliding on said part-cylindrical members to guide said ram for reciprocation.

2. A press for cutting sheet metal comprising an upright C-shaped frame, a work table supported by the lower part of said frame, a plurality of upright pillars supported by the lower part of said frame at points below said work table and extending above said work table, a height-adjustable bracket slidably mounted on said pillars, means for clamping said bracket to said pillars at any desired height above said work table, a plurality of upright part-cylindrical members rigidly secured to said bracket, and a ram having a plurality of grooves of part-cylindrical cross-section formed therein, said grooves co-operating with and sliding on said part-cylindrical members to guide said ram for reciprocation.

3. A press for cutting sheet metal comprising an upright C-shaped frame, a work table supported by the lower part of said frame, a plurality of upright pillars supported by the lower part of said frame at points below said work table and extending above said work table, a height-adjustable bracket slidably mounted on said pillars, tail-pieces extending rearwardly from said bracket, adjusting screws engaging said tail-pieces for raising and lowering said bracket, means for clamping said bracket to said pillars at any desired height above said work table, a plurality of upright part-cylindrical members rigidly secured to said bracket, and a ram having a plurality of grooves of part-circular cross-section formed therein, said grooves co-operating with and sliding on said part-cylindrical members to guide said ram for reciprocation.

4. A press for cutting sheet metal comprising an upright C-shaped frame, a work table sup-

ported by the lower part of said frame, a plurality of upright pillars supported by the lower part of said frame at points below said work table and extending above said work table, a height-adjustable bracket slidably mounted on said pillars, split bosses on said bracket for receiving said pillars, tail pieces extending rearwardly from said bracket, adjusting screws engaging said tail-pieces for raising and lowering said bracket, means for clamping said split bosses to said pillars at any desired height above said work table, a plurality of upright part-cylindrical members rigidly secured to said bracket and a ram having a plurality of grooves of part-circular cross-section formed therein, said grooves co-operating with and sliding on said part-cylindrical members to guide said ram for reciprocation.

5. A press for cutting sheet metal comprising an upright C-shaped frame, a work table supported by the lower part of said frame, a plurality of upright pillars supported by the lower part of said frame at points below said work table and extending above said work table, a bracket rigidly secured to said pillars above said work table, a plurality of upright part-cylindrical members rigidly secured to said bracket, a ram having a plurality of grooves of part-circular cross-section formed therein, and bushes of part-circular cross-section detachably mounted in said grooves, said bushed grooves co-operating with and sliding on said part-cylindrical members to guide said ram for reciprocation.
